UNITED STATES PATENT OFFICE.

JOHN W. MABIN, OF RED WING, MINNESOTA.

FANNING-MILL.

1,309,329.

Specification of Letters Patent.

Patented July 8, 1919.

Application filed March 17, 1919. Serial No. 283,032.

To all whom it may concern:

Be it known that I, JOHN W. MABIN, a citizen of the United States, residing at Red Wing, in the county of Goodhue and State 5 of Minnesota, have invented a new and useful Fanning-Mill, of which the following is a specification.

This invention relates to improvements in fanning mills, the object of the invention 10 being to provide a mill of this character adapted for the separation of grain from straw and chaff, etc., and which mill is dustless in the operation thereof and so constructed that the good grain will be properly separated and delivered at a different 15 outlet from the straw and chaff.

A further object of the invention is to provide a mill of the character set forth, which is comparatively simple in construction, economical to manufacture and extremely efficient in operation.

With the foregoing and other objects in view, which will appear as the description proceeds, the invention consists in the novel 25 features of construction and combination of parts, all of which will be more fully described hereinafter and finally pointed out in the claims.

In the drawings accompanying and forming part of this specification,

Figure 1 is a side elevation of my improved fanning mill;

Fig. 2 is a top plan view thereof;

Fig. 3 is a longitudinal section on an enlarged scale, taken on the line 3—3 of Fig. 2, looking in the direction of the arrows;

Fig. 4 is a vertical sectional view taken on the line 4—4 of Fig. 1, looking in the direction of the arrows; and

Fig. 5 is a rear end elevation of the mill.

The same characters of reference designate the same parts in the different figures of the drawings.

Referring to the drawings, 2 designates 45 the corner uprights or posts forming the framework to which the side walls 3 and end walls 4 are secured. To the lower longitudinal edge of each of the side walls 3 is secured a member 5 which is inclined inwardly toward the center of the casing, and secured to the innermost edge of each of these members 5 is a vertical wall 6 having a portion thereof extending below said members 5 and provided with a bottom 7, thereby forming a trough-shaped channel 8 at

the lower part of the casing. The upper edges of the walls 6 are inclined from front to rear of the casing, and secured to each of these inclined edges is a horizontal bar 9, these bars forming between them an open slot 10 extending from the upper front ends of the walls 6 to the lower rear ends thereof. Secured to the upper sides of the bars 9, contiguous with the edges of the slot 10, are a pair of strips 12 having secured to their lower edges a piece of wire netting 11, which extends over the top of the slot. The strips 12 thus form a vertical channel in communication throughout its length with the slot 10, this channel also communicating at its upper end with an opening formed in a front plate 14 secured between the side walls 3, and at its lower end passes through an opening formed in the rear end wall 4 of the casing, thus forming a continuous chute or channel from front to rear of the casing, as shown in Fig. 3. The outer edges of the bars 9 are spaced from the side walls of the casing, and each of the spaces so formed is covered by a piece of wire netting 13 secured at one of its edges to the bar 9 and at the opposite edge to the side wall 3. At one side of the channel formed by the strips 12, and immediately above one of the bars 9, the front plate 14 is provided with an opening 15, somewhat larger than the opening communicating with said channel, and the rear wall of the casing is also provided with an opening 16 having an inclined bottom 17 extending through the end wall 4, said opening being at a lower level than the channel formed by the strips 12. The rear end of the trough-shaped channel 8 is closed by an end wall 18, and this wall extends up to the bars 9, the extreme ends of such bars being secured to the upper edge of this wall 18, whereby a space is left between the ends of the bars and the end wall 4 of the casing. The end wall 18 is spaced from the end wall 4 of the casing by means of two oppositely inclined strips 19, shown in section in Fig. 3 and in dotted lines in Fig. 5, the converging ends of the strips being secured to opposite sides of the bottom member 17 extending through the opening 16, and which bottom member abuts at its inner end against the wall 18, whereby the opening 16 is placed in communication with the spaces at each side of the strips 12.

Between the front plate 14 and the front wall 4 of the casing, I provide a bottom member 20 extending the full width of the casing, thereby forming a separate compartment communicating with the interior of the casing only through the openings in the front plate 14, and within this compartment are provided a pair of inclined chutes or hoppers, one of which, as 21, is inclined 5 from the front and sides thereof in such manner as to lead only to the central channel formed by the strips 12, the second chute 22 having its upper edge in close contact with the bottom of the chute 21 and so inclined 10 as to lead only to the opening 15 in the front plate 14, the upper front edge of this chute 22 running along the front edge of the casing and extending some distance beyond the front edge of the chute 21, all as 15 clearly shown in Fig. 3.

The main, or what I have termed the interior compartment of the casing is closed by a cover 32, the front end of which is located adjacent to the upper edge of the 20 front plate 14, and in front of this cover and supported over the upper end of the front compartment formed between the front plate 14 and the front wall 4 of the casing, I provide a shaker, designated generally 25 by the numeral 23, which consists in the present instance of a frame having rear and side members, the upper edges of the side members being inclined downwardly toward the front of the casing and provided 30 with a piece of wire netting 24 secured thereto and to the rear member, as shown in Fig. 3. To each of the side members of the shaker is secured the upper end of a strip 25, which is pivoted, as at 26, to the side wall 35 40 of the casing, as shown in full lines in Fig. 1 and in dotted lines in Fig. 3, one of said strips being extended downwardly and bifurcated at its end so as to straddle an eccentric cam 41 carried by the end of a shaft 37 which is journaled in the side walls 45 of the casing and on which shaft the fan is mounted, as hereinafter described, whereby, upon rotation of the shaft the shaker will be rocked back and forth over the compartment 50 above described. Above said shaker is a hopper, designated generally by the numeral 27, so located as to deliver its charge to the rear upper portion of the shaker. This hopper comprises a pair of side walls 55 secured to the top 32 of the main compartment, between which side walls are secured a pair of members 28 inclined in opposite directions so as to form a narrow slot at their adjacent lower edges. A plate 29 having a flange at its upper edge rests on the rear member 28 and is slidably secured thereto by means of a screw 30 passing through an elongated slot in the plate, whereby said plate is adapted to be slid 60 up and down the inclined face of the mem- 65

ber 28, thereby to feed the grain on to the shaker, the upper edge of the member 28 being provided with a finger recess 31 for permitting the flange of the plate 29 to be taken hold of for sliding said plate. 70

Within the lower front part of the casing I have provided a fan chamber, this chamber being located within the space formed between the inner vertical walls 6, each of said walls being provided with a circular opening, as shown at 33 in Fig. 3, for permitting free circulation of the currents of air created by the fan. The fan chamber is formed by means of a metal strip 34 secured at one end to the lower 75 front edges of the vertical walls 6, these edges being curved so as to form, with a pair of segmental extensions 35 secured to the front of the casing, a circular frame around which the strip 34 is secured, the 80 remainder of the strip being secured in close contact with the inner sides of the vertical walls 6, thereby forming a circular chamber for the rotation of the fan, the ends of the metal strip 34 being separated so as to 85 place the fan chamber in communication with the trough-shaped chamber 8 hereinbefore described. Within this fan chamber is mounted for rotation on the shaft 37 a fan having suitably formed blades 36. The 90 shaft may be provided at one end thereof with a pulley 38 for attachment of a belt whereby motion may be imparted to the shaft from some convenient source of power (not shown). The air channel or chamber 95 100 8 may be provided at its rear end with valves for the purpose of regulating the supply of air for different kinds of grain. In the present instance I have shown a pair of hinged doors 39, one at each side of the 105 channel, each of the doors being provided with a projection or rod extending at an angle therefrom and on which is mounted a weight 40 secured to said rod by a setscrew, so that the weight may be set on said rod at 110 different parts of its length, thereby to offer more or less resistance to the opening of the door and the passage of air therethrough.

In the operation of the mill, the shaft 37 is caused to rotate, and thereby the fan and 115 shaker set in motion. Grain is then placed in the hopper 27 and the plate 29 adjusted so as to feed such grain on to the netting or screen 24 of the shaker, which is being rocked back and forth by means of the cam 120 41. This causes the grain to fall through the openings of the screen 24 into the chute 21, being thereby fed down the inclined channel formed between the strips 12, while the straws and chaff pass over the screen 24 125 and fall into the chute 22, which conducts them through the opening 15 in the front plate 14. Meanwhile, the valve doors 39 having been opened sufficiently to supply the required amount of air through the 130

channel 8, the air currents created by the rotation of the fan pass up through the wire netting above the slot 10 and blow all except the good grain into the spaces at each 5 side of the strips 12, the poor grain sliding down the inclined surfaces of the bars 9 and being led by means of the inclined strips 19 out through the opening 16 in the rear wall of the casing, the air passing 10 through the screens 13 back into the fan chamber.

From the foregoing it will be seen that I have provided a fanning mill which is to all intents and purposes dustless, since the 15 main chamber, where the fanning operation takes place is entirely inclosed, and in which the grain is properly separated from the straw and chaff, and while I have described in detail the structure herein illustrated, I 20 do not desire to limit my invention to the precise features of construction shown, as I am aware that many mechanical changes may be made without departing from the spirit and scope of the invention as set 25 forth in the appended claims.

Having thus described my invention, what I claim is:

1. A fanning mill for separating grain from straws and other impurities, comprising 30 an inclosing casing having a main compartment and a front compartment, an inclined channel and an inclined slideway within said main compartment, a pair of hoppers arranged in said front compartment and communicating respectively with said channel and slideway, and means above 35 said front compartment for separating the grain from the straw and other impurities and delivering the grain to one of said hoppers and the straw and other impurities to the other of said hoppers.

2. A fanning mill for separating grain from straw and other impurities, comprising 45 an inclosing casing having a main compartment and a front compartment, said main compartment being provided with a pair of inlets and a pair of outlets, an inclined channel and an inclined slideway within said main compartment and communicating 50 respectively with one of said inlets and with one of said outlets, a pair of hoppers arranged in said front compartment and communicating respectively with said inlets, and means above said front compartment for separating the grain from the straw and other impurities and delivering the grain to one of said hoppers and the straw and other impurities to the other of 55 said hoppers.

3. A fanning mill for separating grain from straw and other impurities, comprising 60 an inclosing casing having a main compartment and a front compartment, an inclined channel and an inclined slideway within 65 said main compartment, a pair of hop-

pers arranged in said front compartment and communicating respectively with said channel and slideway, means above said front compartment for separating the grain from the straw and other impurities and 70 delivering the grain to one of said hoppers and the straw and other impurities to the other of said hoppers, a fan chamber within said main compartment, and a rotatably mounted fan within said fan chamber for 75 creating air currents within said compartment.

4. A fanning mill for separating grain from straw and other impurities, comprising 80 an inclosing casing having a main compartment and a front compartment, an inclined channel and an inclined slideway within said main compartment, a pair of hoppers arranged in said front compartment and communicating respectively with 85 said channel and slideway, means above said front compartment for separating the grain from the straw and other impurities and delivering the grain to one of said hoppers and the straw and other impurities to the 90 other of said hoppers, a fan chamber within said main compartment, and a rotatably mounted fan within said fan chamber for creating air currents within said compartment, said main compartment being provided with a valve-controlled air chamber 95 for supplying air to said fan.

5. A fanning mill for separating grain from straw and other impurities, comprising 100 an inclosing casing having a main compartment and a front compartment, an inclined channel and an inclined slideway within said main compartment, a pair of hoppers arranged in said front compartment and communicating respectively with 105 said channel and slideway, and means above said front compartment for separating the grain from the straw and other impurities and delivering the grain to one of said hoppers and the straw and other impurities to 110 the other of said hoppers, said separating means comprising a screen adapted to be rocked back and forth above said front compartment.

6. A fanning mill for separating grain 115 from straw and other impurities, comprising an inclosing casing having a main compartment and a front compartment, an inclined channel and an inclined slideway within 120 said main compartment, a pair of hoppers arranged in said front compartment and communicating respectively with said channel and slideway, means above said front compartment for separating the grain from the straw and other impurities and 125 delivering the grain to one of said hoppers and the straw and other impurities to the other of said hoppers, said separating means comprising a screen adapted to be rocked back and forth above said front compartment- 130

- ment, and a hopper arranged above said screen and adapted to deliver the grain, straws and other impurities upon said screen.
- 5 7. A fanning mill for separating grain from straw and other impurities, comprising an inclosing casing having a main compartment and a front compartment, an inclined channel and an inclined slideway within said main compartment, a pair of hoppers arranged in said front compartment and communicating respectively with said channel and slideway, rockable means above said front compartment for separating the grain from the straw and other impurities and delivering the grain to one of said hoppers and the straw and other impurities to the other of said hoppers, and means for rocking said separating means.
- 10 8. A fanning mill for separating grain from straw and other impurities, comprising an inclosing casing having a main compartment and a front compartment, an inclined channel and an inclined slideway within said main compartment, a pair of hoppers arranged in said front compartment and communicating respectively with said channel and slideway, rockable means above said front compartment for separating the grain from the straw and other impurities and delivering the grain to one of said hoppers and the straw and other impurities to the other of said hoppers, a shaft rotatably mounted in said casing and carrying a fan within said main compartment, and means carried by said shaft for rocking said separating means.
- 15 9. A fanning mill for separating grain from straw and other impurities, comprising an inclosing casing having a main compartment and a front compartment, a fan chamber within said main compartment, a fan rotatably mounted in said fan chamber, said main compartment being provided with an inclined channel and an inclined slideway in communication with said fan chamber, means in said front compartment communicating respectively with said channel and slideway for delivering the grain to the channel and the straw and other impurities to the slideway, and means above said last-named means for separating the grain from the straw and other impurities.
- 20 10. A fanning mill for separating grain from straw and other impurities, comprising an inclosing casing having a main compartment and a front compartment, a fan chamber within said main compartment, a shaft rotatably mounted in said main compartment, a fan secured to said shaft and adapted to rotate within said fan chamber, said main compartment being provided with an inclined channel and an inclined slideway in communication with said fan chamber, means in said front compartment communicating respectively with said channel and slideway for delivering the grain to the channel and the straw and other impurities to the slideway, rockable means above said last-named means for separating the grain from the straw and other impurities, and means for rocking said rockable means and comprising a pair of strips pivotally secured to said casing, and coöperating means carried by said shaft and one of said strips for rocking the strip on its pivot.
- 25 11. A fanning mill for separating grain from straw and other impurities, comprising an inclosing casing having a main compartment and a front compartment, a fan chamber within said main compartment, a shaft rotatably mounted in said main compartment, a fan secured to said shaft and adapted to rotate within said fan chamber, said main compartment being provided with an inclined channel and an inclined slideway in communication with said fan chamber, means in said front compartment communicating respectively with said channel and slideway for delivering the grain to the channel and the straw and other impurities to the slideway, means above said last-named means for separating the grain from the straw and other impurities, said means comprising a rockable screen, a pair of strips secured to said screen and pivotally secured to said casing, and a cam carried by said shaft and adapted to coöperate with one of said strips for rocking the same on its pivot.
- 30 12. In testimony that I claim the foregoing as my own, I have hereto affixed my signature in the presence of two witnesses.
- 35 JOHN W. MABIN.
- 40 Witnesses:
- 45 THOMAS MOHN,
REX A. HAGERSTROM.
